CLAIM

The ornamental design for a portfolio light, as shown and described.

DESCRIPTION

FIG. 1 is a top view of a portfolio light showing the new design in an example portfolio;

FIG. 2 is perspective view of the portfolio light;

FIG. 3 is a front view of the portfolio light;

FIG. 4 is a right side view of the portfolio light;

FIG. 5 is a left side view of the portfolio light;

FIG. 6 is a top view of the portfolio light;

FIG. 7 is a bottom view of the portfolio light; and,

FIG. 8 is a rear view of the portfolio light.

The broken line showing an example portfolio is for illustrative purposes only and forms no part of the claimed design.
